PLATE CASTING AND FINISHING MACHINE

Original Filed Jan. 28, 1927 3 Sheets-Sheet 3

UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

PLATE CASTING AND FINISHING MACHINE

Application filed January 28, 1927, Serial No. 164,227. Renewed September 25, 1929.

This invention relates to a machine for casting a curved stereotype printing plate and preparing the interior of the plate while in the mold for application to the plate cylinder. The principal objects thereof are to provide a machine which will cast the plate and then finish the concave side of the plate while it is in the mold, backed up against the matrix against which it is cast, and then 10 eject the plate from the mold and bring both the plate and the matrix out where the matrix can be stripped from the plate and the plate removed, and especially to perform all of these operations by a single rotation of the 15 core. The invention also involves the operation of a casting bar at the lower edge of the plate to maintain it in position while the ribs on the back of the plate are being smoothed down on the concave side and allow it to be 20 removed automatically when that operation is completed to allow the plate to be ejected.

Other objects and advantages of the invention will appear hereinafter.

Reference is to be had to the accompanying drawings in which

Fig. 1 is a side elevation of a machine constructed in accordance with this invention;

Fig. 2 is a transverse sectional elevation showing the parts in the position in which the casting has been completed and the tail is broken off the casting ready for the next operation;

Fig. 3 is a similar view showing the core partly rotated and the inside of the plate 35 partly finished;

Fig. 4 is a similar view showing the parts about 180° from the position shown in Fig. 3 with the plate entirely finished and the core rotated around to a position in which 40 the plate has started to be ejected from the back;

Fig. 5 is a similar view showing the plate entirely ejected and the matrix being stripped therefrom; and

Fig. 6 is a sectional view of the means for operating the casting bar, the position here being intermediate between the positions shown in Figs. 3 and 4.

In my prior application, Serial No. 632,639, filed April 17, 1923, I have shown a machine of

this type in which the plate, together with the matrix, is ejected from the box by the first half revolution of the core so that the matrix can be stripped from the plate, then the plate during the next half revolution is 55 entered into the mold in the place it formerly occupied. On the start of the second revolution of the core, the plate was shaved by a knife carried by the core and on the second half of the second revolution the plate was 60 finally ejected ready to be removed. Two revolutions of the core were required to complete the cycle of operations necessary to make a finished plate and present it in a position to be removed from the mold. 65

In this invention these operations are accomplished in a single revolution of the core, thus simplifying the machine in many respects.

I have shown the invention as applied to 70 a machine mounted on a frame 9 provided with a power driven shaft 10 which rotates constantly. This shaft is provided with a rotating clutch section 11 slidably keyed to it and adapted to be moved by a hand clutch 75 lever 12 into position to clutch it to a worm 13 rotatable and freely mounted on the shaft 10. This worm operates a worm wheel 14 fixed on a shaft 20 and causes that shaft to rotate when the lever is moved in to connect 80 the clutch. This lever 12 is provided with a lug 15 which is controlled by a cam 16 having a notch for receiving the lug 15, this cam being fixed on the worm wheel or shaft 20. Therefore when the worm wheel and the 85 shaft 20 have rotated a complete revolution the hand lever can be moved in to release the clutch and stop the machine.

The machine as shown comprises a stationary concave back 21 for receiving a matrix M against which the metal is to be cast to form a printing plate. The flat face of the back is located at an inclination so the metal can be introduced along a straight edge at the top. The other side of the mold is formed by a convex core 22 of semi-cylindrical form fixed on the shaft 20 and rotating with it. The axis of the mold is horizontal. The back and core may be water-cooled but the details are not shown herein. 100

The semi-cylindrical mold formed by these two parts is provided on each straight edge with a radially slidible matrix bar 25.

On a shaft 26 is pivotally mounted a casting bar 33. This is shaped to cover the edge of the matrix bar, grip the edge of the matrix thereto, and seal that edge of the mold. This bar with the two hubs by which it is mounted on the shaft 26 and projections 34 constitutes a lever. Two springs 35 are provided, connected with stationary lugs 36 on the back for normally holding this bar out of casting position as shown in Fig. 5. On the shaft 20 is a cam projection 27 which engages a lever 28 having a hook 29 for engaging a lug 30 on the casting bar 33 and normally holding the casting bar in position to seal the lower edge of the mold as shown in Figs. 2 and 3. Once during each revolution of the shaft 20 the projection 27 unlocks the bar and then the springs 35 pull it into open position as shown in Fig. 5.

On the pouring side the mold is provided with a pouring gate 37 the details of which will not be described herein as any gate can be employed. I prefer to use a gate described in a prior application Serial No. 108,632, filed May 12, 1926, which operates to break off the tail of the plate as shown in Fig. 2 and leave the plate ready for the rest of the operation. The matrix bars 25 are forced inwardly to clamp the edges of the matrix by cams 41. One of these cams is located on the shaft 26 and the other on a parallel shaft 26^a connected to operate simultaneously with the shaft 26. The latter is operated by a handle 42. The pouring spout 37 cooperates with the upper matrix bar to hold that edge of the matrix.

The core which is semi-cylindrical in form, is provided with an ejecting bar 38 arranged radially and fixed to the lower edge of the core as it appears in casting position. This cooperates with the bars 25 and 33 to complete the lower edge of the mold. The core is also provided with a bar 39 arranged radially at the opposite side of the core for smoothing the interior of the plate. Likewise the core is provided with a projection 40 for supporting the plate when it is ejected from the mold as shown in Fig. 5.

The operation of the machine is as follows:

In Fig. 2 the mold is shown closed and filled with metal and also the pouring gate 37 is shown shifted laterally to break off the tail and release the upper edge of the matrix. This gate is manipulated to get rid of this tail by turning the handle 42 which through an arm 43 and link 44 raises the gate and moves it out of the way of the rotating parts during their subsequent operation. This operation also turns the shafts 26 and 26^a to release the edges of the matrix.

Now the operating handle 12 is moved

back to move the lug 15 from the notch in the cam 16 and close the clutch. The shaft 20 now rotates a complete revolution, the first part of which is indicated in Fig. 3. Here the bar 39 is shown as smoothing the interior ribs of the plate and bringing them down to a cylindrical surface ready to be applied to the printing cylinder of the press. The casting bar 33 remains in closed position at this time on account of the latch or hook 29. When half a revolution has been completed, the plate is entirely finished on the back. At this time the projection 27 engages the lever 28, lifts the hook 29 and frees the casting bar 33. The springs 35 pull this bar back and at the same instant the ejecting bar 38 comes around and engages the rear of the plate at the top. The position of the parts just after this occurs is shown in Fig. 4.

Now the plate with its matrix is being ejected on the second half of the first revolution of the shaft 20. The end of that operation is shown in Fig. 5. The plate is supported by the projection 40 on the shaft 20. The matrix can be taken off, then the casting removed in any desired direction and the matrix put back in the mold. The handle 42 is brought back to the position shown in Fig. 2 and the matrix bar 25 at the bottom and the corresponding bar radially opposite at the top are forced in by the cams 41. The pouring spout or sprue 37 is brought down by the same operation into casting position and the machine is ready for a second cycle of operations.

This accomplishes the results of the above specified application by one rotation of the shaft 20 and thus simplifies the organization of the machine. The machine is stopped when a complete rotation is finished by holding the starting lever in position for the lug 15 to rest against the core cam 16 and enter the notch therein when it registers with it. This necessitates the separation of the clutch just at the time when a complete revolution is made and prevents its stopping at any other point. The ribs on the back or concave face of the plate are shown in this case as being smoothed off to a uniform surface by pressure of the bar 39 having a comparatively blunt edge, instead of being shaved off in the usual way. It is to be understood, however, that a sharp shaving blade can be used without reorganizing the machine in any way. The pouring gate 37 can be operated as in a prior application of Hans C. Jordhoy, Serial No. 108,632, filed May 12, 1926.

Although I have illustrated and described only a single form of the invention I am aware of the fact that modifications can be made therein by any person skilled in the art without departing from the scope of the invention as expressed in the claims. Therefore, I do not wish to be limited to all the

details of construction herein shown and described, but what I do claim is:—

1. The combination with a stereotype plate casting back of segmental form, of a core having a convex surface rotatable therein between which and the back the plate is adapted to be cast, means rotatable with the core for smoothing the interior of the plate in the back as the core is rotated through the first half revolution, and means rotatable with the core for ejecting the plate.

2. The combination with a stereotype plate casting mold of semi-circular shape, of a core cooperating with the back to complete the mold cavity and rotatable on the axis of the back, means for rotating the core a complete revolution and then stopping it, and means on the core and rotatable therewith whereby as the core rotates through the second half revolution the plate will be moved with it out of the back to expose the matrix thereon for stripping, said core being provided with means for smoothing the interior of the plate as it rotates through the first half revolution.

3. The combination with a stereotype plate casting back of segmental form, of a core having a convex surface rotatable therein, means rotatable with the core for smoothing the interior of the plate while the plate rests against the back in its original casting position therein against the matrix and means on the core and rotatable therewith for ejecting the matrix.

4. In a curved stereotype plate casting mold, the combination with a semi-cylindrical rotatable core and a semi-cylindrical back, of a bar on one edge of the core adapted to shape the interior of the plate as the core rotates through half a revolution, and a bar located on the opposite edge of the core adapted to engage the rear edge of the plate and eject it as the core rotates through the second half of a complete revolution.

5. The combination with a stereotype plate casting mold comprising a back and core, both semi-cylindrical, of a pair of matrix bars along the opposite straight edges of the mold adapted to slide radially toward each other to engage the straight edges of the matrix, an operating handle, and means connected with the operating handle for positively moving both matrix bars inwardly.

6. In a semi-cylindrical stereotype plate casting mold, the combination with a semi-cylindrical core and back, of means for rotating the core a complete revolution, a casting bar mounted to swing on a pivot and adapted to move into a position to close one straight edge of the mold, a latch for holding the casting bar in its closed position, means rotatable with the core for holding the casting bar during part of the revolution and for releasing it at a definite point in the revolution of the core.

7. In a semi-cylindrical stereotype plate casting mold, the combination with a semi-cylindrical core and back, of means for rotating the core a complete revolution, a casting bar mounted to swing on a pivot and adapted to move into a position to close one straight edge of the mold, a latch for holding the casting bar in its closed position, means rotatable with the core for holding the casting bar during part of the revolution and for releasing it at a definite point in the revolution of the core, and means on the core, normally cooperating with the casting bar for closing that end of the mold, and in a position to engage the opposite straight edge of the casting when the core has rotated through a half revolution to eject the casting from the mold in a circumferential direction immediately after the latch is released.

8. In a stereotype plate casting mold, the combination with a back and core, both semi-cylindrical in shape and arranged with their flat sides at an inclination to the horizontal, of a casting ejecting bar fixed on the core and located radially in position to project over the lower end of the mold cavity, a matrix bar projecting over the same end of the mold cavity from the other side, and a casting bar movable to a position between said bars to completely close the mold and having means for holding the matrix bar in position.

9. In a stereotype plate casting mold, the combination with a back and core, both semi-cylindrical in shape, of a casting ejecting bar fixed on the core to project over the end of the mold cavity, a matrix bar projecting over the same end of the mold cavity from the other side, and a casting bar movable to a position between said bars to completely close the mold.

10. The combination with a stereotype plate casting back of segmental form, of a core having a convex surface rotatable therein between which and the back the plate is adapted to be cast, means rotatable with the core for smoothing the interior of the plate in the back as the core is rotated through the first half revolution, and means on the opposite edge of the core from the smoothing means adapted to engage the rear edge of the plate and eject it as the core rotates through the second half of a complete revolution.

11. The combination with a stereotype plate casting mold of semi-circular shape, of a core cooperating with the back to complete the mold cavity and rotatable on the axis of the back, means for rotating the core a complete revolution and then stopping it, said core being provided with means for smoothing the interior of the plate as it rotates through the first half revolution, and means on the opposite edge of the core from the smoothing means adapted to engage the rear edge of the plate and eject it as the core rotates through the second half of a complete revolution.

plate and eject it as the core rotates through the second half of a complete revolution.

12. The combination with a stereotype plate casting back of segmental form, of a core having a convex surface rotatable therein, means rotatable with the core for smoothing the interior of the plate while the plate rests against the back in its original casting position therein against the matrix and means on the opposite edge of the core from the smoothing means adapted to engage the rear edge of the plate and eject it as the core rotates through the second half of a complete revolution.

13. In testimony whereof I have hereunto affixed my signature.
